RODLINE COUPLER

William R. Barney, Fort Worth, Tex., assignor to
W. C. Norris, Tulsa, Okla.

Application April 28, 1934, Serial No. 722,909

7 Claims. (Cl. 74—593)

My invention relates to new and useful improvements in a safety coupling device for a power rodline for operating a pump jack, and has for its objects to provide a cheap and simple means of connecting and disconnecting the rodline and of adjusting the length thereof and of adjusting the position of the pump jack with relation to the stroke of the rodline.

With the above and other objects in view which will be disclosed as the description proceeds, my invention consists in the novel features herein-after set forth, shown in the accompanying drawing and more particularly pointed out in the appended claims.

15 Referring to the drawing in which like numerals designate similar parts thruout the several views:

Fig. 1 is a view in side elevation of my coupling device with the same uncoupled.

20 Fig. 2 is a view of the same when coupled.

Fig. 3 is a top plan view of the same when the device is uncoupled.

25 Fig. 4 is a view in cross section on line A—A of Fig. 3, except for the omission of the knockoff portion thereof.

1 represents that portion of a power rodline connected to the pump jack, and 2 that portion thereof connected to the power. 3 represents a knockoff plate member which is connected to line 1, and 4 represents a hookon or hookon member in the form of a bail or loop which is connected to line 2. 5 represents a knockoff post whereon is slidably mounted a knockoff bar 6 having a handle 7 thereon. In the under edge 30 of plate 3 is a series of notches 8, each of which notches is adapted to receive and hold loop 4. The upper edge of plate 3 provides a track 9 whereon a rest support for loop 4 may slide or roll when said loop is disengaged from said plate.

40 For slidably supporting loop 4 when it is disengaged from plate 3, and for holding it in position for immediate engagement with said plate, I have provided as a preferred form of my invention, a bent lever 10 fulcrumed on a pin 11 which also serves as the axle of a roller or wheel 12, and with said lever having at its weight bearing point another pin 13 which serves as the axle of a roller or wheel 14 and also as a pivot pin to which loop 4 may be pivotally connected to lever 10 and wheel 14 by means of straps 15; all of which structure is arranged so that when loop 4 is disengaged from plate 3 it remains slidably suspended from and in close relationship to said plate and with roller 14 45 supporting it on top of said plate and with rollers 12 and 14 free to travel on track 9 when

said loop is reciprocated by the action of the power to which it is connected thru line 2. It is obvious that in place of rollers or wheels as aforesaid, slides or slide blocks may be employed, and that roller 12 or its equivalent slide may be omitted inasmuch as the weight of loop 4 is carried by roller 14 and roller 12 serves as a support for the fulcrum of lever 10, in which event the lever would be free to fulcrum on track 9. Moreover it is evident that the pivotal connection of straps 15 might be made to lever 10 thru a separate pin located thereon between the two wheels aforesaid, and that the gist of my invention resides in providing a slidable support for loop 4 when the same is disengaged 5 and in providing said support in manner such that said loop may be safely, quickly and conveniently hooked into any one of the desired notches 8 of plate 3.

In plate 3 and towards the end thereof to 20 which line 1 is connected, are notches 16, similar to notches 8 and adapted to receive knock-off bar 6 as shown in Fig. 1. In practice no distinction is made between notches 8 and 16 and all may be spaced alike in one series. The spacing is preferably such that when in use the loop 4 may be thrown into any one of several notches within its reach, and the knockoff bar 6 may be slipped into any of the notches which the movement of plate 3 may permit.

30 In use, when the well is hooked on, that is when the rodline is connected as shown in Fig. 2, the knockoff bar 6 is disengaged from plate 3 and the hookon loop 4 is engaged in one of the notches 8. When it is desired to knock the well off, that is to disconnect the rodline, the operator pulls handle 7 upwardly to engage bar 6 in a selected notch 16 as the rodline moves towards the pump jack, whereupon the movement of line 1 is checked, but as the power continues to move line 2 it shoves loop 4 out of notch 8 in which it rests and the weight of the loop causes it to drop downwardly until roller 14 engages track 9, whereupon loop 4 hangs suspended from plate 3 and lever 10 is in the position shown in Fig. 1, in which position the lever and loop ride on plate 3 as the power causes loop 4 to continue to be reciprocated.

With the well knocked off and the power in operation, when it is desired to hook the well on, the operator presses down on lever 10 at its 50 free end and thus causes loop 4 to come into engagement with any desired notch 8 which it may pass during its travel, whereupon with the movement of the loop in a direction towards the power the knockoff bar 6 becomes disengaged 55

from notch 16 wherein it has been held and the bar drops free from plate 3.

When it is desired to pick up the well, that is to raise the jack to its working position as for example when the jack has been dropped by reason of the rodline parting or the jack has been let down to service the well, the jack may be picked up or pulled into its working position by manipulating lever 10 which controls the hook 10 on and handle 7 which controls the knockoff, in which operation plate 3 is first run back towards the jack far enough to connect the rodline, then lever 10 is thrown to engage loop 4 in the notch which is farthest within its reach, then as plate 3 is pulled towards the power one or more of the notches 16 come up to or pass the knockoff bar 6 and as the last notch passing the bar commences to move in reverse direction bar 6 is slipped into it, whereupon loop 4 becomes disconnected from plate 3 and is then free to engage another notch closer to the one then holding bar 6 and upon so engaging such notch plate 3 is again moved closer to the power and the knockoff bar 6 may be slipped into another notch closer to the jack than was the notch in which it was first placed. In this manner the length of the rodline between the power and the jack may be adjusted to place the jack in the desired working position. The jack may be let down by reversing the operation.

Having thus fully described my invention, what I claim and desire to secure by Letters Patent is:

1. In a coupling device for connecting and disconnecting a power rod line, a knockoff member, a hookon member positioned below said knockoff member, means on said hookon member for securing the hereinafter mentioned lever thereto, a lever as aforesaid connected to said means and adapted to raise said hookon member into engagement with said knockoff member, and means on said lever for slidably holding said hookon member in an immediate engageable position with said knockoff member when said device is uncoupled.
2. In a coupling device for connecting and disconnecting a power rodline as claimed in claim 1, and a wheel on said lever adapted to travel on said knockoff member and to support

said hookon member when the device is uncoupled.

3. In a coupling device for connecting and disconnecting a power rodline as claimed in claim 1, a wheel on said lever adapted to travel on said knockoff member and to support said hookon member when the device is uncoupled, and a second wheel on said lever adapted to travel on said knockoff member and to serve as the fulcrum of said lever.

4. In a coupling device for connecting and disconnecting a power rodline, a plate knockoff member having a plurality of notches in its under edge and having a comparatively straight upper edge constituting a track, a hookon member having thereon means adapted to engage a selected notch of said plurality of notches in said knockoff member, means on said hookon member slidably engaging said track for suspending said hookon member in spaced position with said knockoff member when said device is uncoupled and a lever pivotally connected to said means for raising said hookon member into engagement with said selected notch.

5. In a coupling device for connecting and disconnecting a power rodline as claimed in claim 4, and with one of the last aforementioned means being a wheel on said lever adapted to travel on said knockoff member and to support said hookon member when the device is uncoupled.

6. In a coupling device for connecting a power rodline as claimed in claim 4, and a wheel on said lever adapted to travel on said knockoff member and to serve as the fulcrum of said lever.

7. In a coupling device for connecting and disconnecting a power rodline, an elongated plate knockoff member having a track along the upper edge and a series of notches along its lower edge, a hookon member adapted to engage any selected notch aforesaid in said knockoff member, and a rest support on said hookon member adapted to slidably rest on said track and support said hookon member in an immediate engageable position with said knockoff member when said device is uncoupled, and with a roller on said rest support adapted to travel on said track and to support said hookon member as aforesaid.

WILLIAM R. BARNEY.
